UNITED STATES PATENT OFFICE.

MARIE J. O'ROURKE, OF HANFORD, CALIFORNIA.

GOLF-BALL-RETRIEVING DEVICE.

Application filed November 15, 1926. Serial No. 148,425.

This invention relates to a golf ball retrieving or recovering device, designed for lifting or removing the ball from the greens cup after holing out.

6 The invention consists broadly in operatively associating a spoon or cup with a golf club shaft, preferably a putter shaft, the club employed in holing out on the respective greens, whereby the spoon or cup 10 is available immediately after holing out for insertion into the greens cup to lift the holed ball therefrom, without necessitating the player stooping or soiling the hands should the greens cup contain water, which is often 15 the case.

The invention has for its principal object to provide a cup or spoon associated preferably with the grip end of a putter shaft, and by the employment of which the player, 20 after holing out the ball, may invert the club shaft, and with the assistance of the spoon or cup remove the ball from the greens cup.

Another object is to provide a spoon or 25 cup for association with a golf club shaft, and which will not interfere with the normal use of the club in playing the game and which will always be available for recovering the ball immediately after holing out.

30 Another and important object is to provide a structure of the class described which will be neat and compact in appearance, one which is capable of being cheaply manufactured from any desired material, and one 35 which is preferably adapted for ready attachment to the club shaft without the necessity of special tools and without altering the shaft in any manner.

With the above mentioned and other objects in view, the invention consists in the 40 novel construction and combination of parts hereinafter described, illustrated in the accompanying drawings, and set forth in the claims hereto appended, it being understood 45 that various changes in the form, proportion, size and minor details of construction within the scope of the claims may be resorted to without departing from the spirit or sacrificing any of the advantages of the 50 invention.

To more fully comprehend the invention, reference is directed to the accompanying drawings, wherein

Fig. 1 is a view in perspective of one embodiment of my invention. 55

Fig. 2 is a similar view of a slightly different form.

Fig. 3 is a view in perspective of the invention illustrated in Fig. 1 and positioned 60 on the grip end of a putter shaft.

Figure 4 is a similar view of the embodiment illustrated in Fig. 2 in position on the grip end of a putter shaft.

Referring to the drawings wherein like 65 characters of reference designate corresponding parts throughout the several views, 1 indicates the shaft of a golf club, preferably a putter. The shaft mounts at one end a head 2 preferably of the type employed for putting or holing the ball out 70 on the green. The shaft 1 carries at its opposite end a conventional grip 3, and while the club is illustrated and described particularly as a putter, it is to be understood that any club used at the time the ball 75 is holed out on any given green may suffice.

Referring to Figs. 1 and 3, the numeral 4 indicates a longitudinal split spring collar 80 adapted to frictionally engage the grip end 3 of the club shaft when the collar is slipped thereover. The collar 4 mounts a cup or spoon structure of any suitable type, the same in the present embodiment consisting of a wire frame structure 5 illustrated as 85 consisting of three wires, two forming the side wall members and one the base or bottom, the ends 6 of the wires lying in parallel relation and secured at 7 to the collar 4 so that the open mouth of the frame will lie in a plane parallel with the surface of the collar 4, and when the device is positioned on the club shaft 1 the cup or spoon will extend 90 from the end of the shaft in alignment with its axis. It will be understood that this wire frame structure which projects but a slight 95 distance from the end of the club shaft in no way interferes with the normal use of the club, and enables the player after holing out to invert the club and insert the cup or spoon into the greens cup and quickly remove the holed ball therefrom. 100

In Figs. 2 and 3, the cup or spoon is illustrated in the form of a metallic stamping or casting 8, preferably of one piece construction, but such is not an absolute essential. 105 This cup structure has associated therewith

a suitable attaching screw 9 extending therefrom at right angles to the plane of the cup and said screw shaft 9 is adapted for threading into the grip end of the club shaft at 10 5 to detachably mount the cup or spoon thereonto.

It will be observed that while two embodiments of the invention are here illustrated, other modifications may be employed so long as the inventive idea of the incorporation of the spoon or cup in connection with the club shaft is carried out.

It will be observed that both embodiments of the invention are readily attached to and detached from the club shaft, and each may be cheaply manufactured and efficiently conserved for the purpose intended without in any manner interfering with the normal use of the club by the player, or the positioning into or removal of the club from the conventional golf club bag.

I claim:—

1. A golf ball retrieving device comprising

an open frame constituting a cup, and means extending laterally from the edge of the cup 25 for yieldably and detachably gripping the shaft of a golf club with the cup projecting from the end of the club in alignment with the axis of the shaft.

2. A golf ball retrieving device comprising 30 a member arranged with its ends in parallel adjacent relation and its body bent to provide an open cup frame, a second member arranged with one end adjacent to the ends of the other member and its other end secured to the other member within its cup frame forming bend, said latter member between its ends being bent laterally to one side of the cup frame to provide a bottom member for the cup frame, and a longitudinally 40 slit collar longitudinally of one surface of which said member ends are secured.

In testimony whereof I have signed my name to this specification.

MARIE J. O'ROURKE
